UNITED STATES PATENT OFFICE.

FRANK OTTO MOLL, OF PORTLAND, OREGON.

FURNACE.

1,132,372

Specification of Letters Patent. Patented Mar. 16, 1915.

Application filed March 14, 1913. Serial No. 754,210.

To all whom it may concern:

Be it known that I, FRANK O. MOLL, a citizen of the United States, and a resident of Portland, in the county of Multnomah and State of Oregon, have invented a new and Improved Furnace, of which the following is a full, clear, and exact description.

My invention relates to furnaces of the "warm-air" type, and the object thereof is to produce a heater of this nature which will be very efficient and economical in action, easily cleaned, proof against leakage through its walls of the gases generated therein, and so constructed that the parts thereof can readily be replaced when any of them are worn out. To this end I make the smoke conduits or flue tubes of my furnace preferably of thin metal, since by reason of such construction these flue tubes have a shorter life than a heavier metal construction. I support the same in place by means facilitating their removal and renewal as often as required.

A further object of my invention is to produce a furnace or heater of the type mentioned which will readily radiate heat, require comparatively little fuel in operation and be capable of using a lower grade of fuel than is usually required for similar furnaces now on the market.

Reference is to be had to the accompanying drawings forming a part of this specification, in which the same characters of reference indicate the same parts in all the views.

Figure 1 is a vertical longitudinal section of my furnace; Fig. 2 is a vertical transverse sectional view on the line 2--2 of Fig. 1; Fig. 3 is a horizontal sectional view on the line 3--3 of Fig. 1; Fig. 4 is a horizontal sectional view on the line 4--4 of Fig. 1; Fig. 5 is a horizontal sectional view on the line 5--5 of Fig. 1; Fig. 6 is a sectional view on the line 6--6 of Fig. 1, and Fig. 7 is a detail showing how the ends of the heating pipes are secured to the plate shown in Fig. 6.

My improved heater comprises an outer casing the sides of which are shown at 1 closed by a top 2 and resting upon a base 3. Inside of this casing is built a fire-box 4, and the gases of combustion are led therefrom by means of a flue 5 which communicates with the casing and fire-box 4 at the rear. The casing contains a number of heat-

ing tubes 6 arranged in two horizontal layers, and in operation the hot gases of combustion first pass through the upper layer and then down through the lower layer before they reach the flue 5 and pass out. The air to be heated passes into the casing through an opening 7 which is shown as being located at the rear, and the course taken by this air is such that it comes into contact both with the fire-box and the heating tubes 6 before it can pass out through the flues 8 which lead from the top of the outer casing of the furnace to the apartments to be heated.

The fire-box is of course made of metal and it is lined with firebrick or any other suitable refractory material shown at 9. Through its front it has an opening which is connected by means of an annular web 10 to an opening leading through the front of the outer casing of the furnace that is normally closed by means of a swinging door 11, and this web 10 is bolted both to the front of the casing and to the fire-box 4, as will be readily understood, suitable flanges being provided for this purpose.

Inside the fire-box 4 below the lining 9 is a grate 12 which marks the top of the ashpit, and access to the ashpit can be had through the passage 13, which is closed by another swinging door 14 below the door 11. This passage 13 is formed by means of a web similar to the web 10 bolted both to the fire-box and the front of the casing, which have openings therethrough, as will be readily understood. The bottom of the ashpit is formed by means of an inclined plate 15, and the base 3 may have an opening 16 therethrough directly below the ashpit, as shown in Fig. 1.

The fire-box 4 has an outlet opening through the back near the top, and around this outlet opening is secured a cast iron collar 17. This collar abuts against the outer end of another cast iron collar 18 secured around an inlet opening to a radiator 19 which is located adjacent the back of the casing 1 and supported upon standards 20. This radiator 19 is preferably made of steel plates, and the gases of combustion pass through the radiator on their way to the heating tubes 6.

At the top of the casing 19 are suitable openings shown as three in number located in the front wall and are surrounded by means of cast iron collars 21 having flanges

which are bolted to the front of the radiator, these collars receiving the rear ends of the heating tubes 6. These collars are preferably tapering in form and receive the ends 5 of the tubes 6 which fit tightly around the same. The upper layer of heating tubes therefore is composed of three tubes and the front ends thereof are supported by means of a plate 22 which has a flange forming a 10 foot 24 resting upon the top of the fire-box 4 and having its upper edge secured to a transverse flange 23 on the lower side of the top 2. A transverse horizontal plate 25 may be employed to extend from one side of 15 the casing to the other in the front of the plate 22 at the bottom thereof, resting upon the foot 24 and upon a corresponding rib 26 formed on the inner face of the front of the casing, and this plate, together with the 20 plate 22, will form a closed chamber into which access cannot be had from the lower part of the casing 1. In consequence the hot gases passing into the radiator 19 and through the upper layer of tubes 6 cannot 25 pass out through the bottom of the chamber formed by the plates 22 and 25 and portions of the top and front of the casing, nor can any air entering the casing through the opening 7 pass into the chamber from below. 30 The lower layer of heating tubes 6 is shown as consisting of two tubes, and these tubes are likewise supported at their inner ends by having the said inner ends slipped over collars 21 secured to the front wall of 35 the radiator below the first-mentioned collars 21. The lower tubes are staggered with respect to the upper tubes and their front ends are supported by the plate 22 in the same manner, this plate having apertures 40 through which the front ends project a slight distance.

The wall forming the web or partition 22 is connected to the front wall of the radiator 19 by means of rods 27, and in order to 45 make a perfectly tight fit between the front ends of the tubes 6 and the apertures in the plate 22 receiving them, I employ conical rings 28. The tubes 6 may be of steel or sheet iron and the collars 28 of malleable iron heavy enough to retain their shapes and be capable of being ground to a true circle so that they will fit the tubes. On account 50 of their conical shape they press the material forming the front ends of the tubes 6 into tight contact with the edge of the openings in the plate 22 and form a perfectly leak-proof joint. A swinging door may be formed in the front of the casing near the top, this door being shown at 29, to give access to the front of the tubes 6 or to the chamber into which the front ends of these tubes open, when necessary.

The radiator casing 19 is provided with a transverse flue 30 which is wide enough to 65 communicate with the ends of both of the

lower tubes 6, and this tube fits tightly against the front wall of the radiator and is supported at its rear end by means of a suitable rib 31 formed on the inner face of the rear wall of the radiator. The flue 30 70 communicates centrally with an outlet opening surrounding which is a cast iron collar 33 similar to the collars 21 bolted to the outside of the rear wall of the radiator 19 and extending through an opening in the 75 rear wall of the outer casing. Over the outer end of this collar is slipped a conduit 32 which forms a branch of the flue 5, so that the gases after passing through the upper and lower tubes can then pass out through 80 the smoke flue.

The radiator 19, as will appear from an inspection of Figs. 3, 4 and 5, is shaped in cross-section like the segment of a circle, and the flue 30 does not obstruct the passage of gases upward through the radiator 85 because there are spaces on either side of this flue through which the gases of combustion can pass on their way to the upper tubes 6. After passing through these upper tubes 20 they reach the chamber formed in the upper part of the front of the casing and turn downward to pass through the lower tubes and the flue 30 and then out of the furnace to the chimney. 95

At the lower part of the radiator 19 and in line with the collars 17 and 18 is an opening which is associated with a collar 35 bolted to the rear wall of the radiator and passing through an opening at the rear of 100 the casing 1 above the opening 7. In this collar is mounted a suitable damper 36, and the lower end of the smoke flue 35 will be provided with a transverse extension which is slipped over the outer end of the collar, 105 and when the damper 36 is open some of the gases can be allowed to escape directly through the flue 5 instead of passing upward through the tubes 6.

The inside of the casing 1 carries deflector 110 plates 37 which are secured at the sides and normally extend upward at a slight inclination, approximately to the sides of the outer tubes 6 in the upper layer. Their function is to prevent air passing in through the 115 opening 7 from passing out through the tubes 8 without first coming into contact with the heating tubes 6, and I can regulate this heating effect by changing the position of the plates, so that a greater or less quantity of air can be caused to pass through the 120 casing without coming into direct contact with the heating tubes.

As shown in Figs. 3, 4 and 5, the horizontal cross-sectional shape of the furnace is 125 approximately circular. The walls of the casing 1 are made of plates of suitable thickness and the casing may be provided with an extended front which is closed by means of a plate 39. The lower end 40 of 130

this plate may be received in a groove 38 in the base 3, the base being extended in front to correspond with the extension of the casing, and the plates forming the bottom of the casing around the sides and back will be held in place by an annular rib 41 on the base 3, which will pass around the bottom edges of the sides and back of the casing and engage the same.

16 When malleable iron conical rings 28 are driven into the ends of these tubes, the seams of the latter permit sufficient expansion to cause the outer sides of the tubes to have a gas-tight-contact with the edges of the open-
ings in the plate 22.

15 The operation of my furnace will now be clear. When there is a fire, air passing in through the opening 7 first comes into contact with the walls of the fire-box, collars 17 and 18 and the tubes 6, passing out through 20 and the tubes 6, passing out through the flue 30 after being heated. The hot gases of combustion pass through the collars 17 and 18 in the radiator 19 up past the flue 30 into the upper tubes 6, then toward the front 25 of the furnace, then downward through the lower tubes 6 and out through the flue 30 and the collar 33 into the flue 5. The damper 36 gives a direct draft through the chimney when open and is useful when the fire is 30 to be started or replenished, as will be readily understood.

From the above description it will be seen that my furnace is so constructed that it can be readily cleaned and kept clean at all 35 times, and in case of the parts becoming worn and having to be replaced the replacement can be easily effected. Further, on account of the large extent of radiating surface into contact with which the air passes 40 on its way through the casing 1, I do not require as hot a fire to get a good heating effect. I can also use a cheaper grade of coal or other fuel, such as wood.

On account of the manner in which my 45 furnace is constructed the leakage of gases from the fire-box into the cellar or other apartment in which the same is operated is impossible. The doors are all arranged so as to fit tightly the openings which they 50 cover, and the radiator 19, the fire-box 4 and all of the flues through which the gases pass on their way through the furnace and out of the same are made with leak-proof joints.

It will be seen from the manner in which 55 the tubes 6 are arranged that the hot gases when they reach the top of the furnace are spread out to a considerable extent, and the air to be heated thus passes not only around the tubes but among them. It is this construction which gives a thorough and efficient effect.

I wish to have it understood that the above description is illustrative only and discloses but one embodiment of my invention, and I 60 do not care to be limited to the exact details

shown and described, but reserve to myself the right to make such changes in the shape, size and arrangement of the parts as fairly fall within the scope and spirit of my invention.

70

Having thus described my invention, I claim as new and desire to secure by Letters Patent:

1. In a hot air furnace, a casing having an air inlet at its rear lower portion, a fire box 75 in the lower front portion of the casing, a radiator in the rear portion of the casing above the air inlet and extending to the top of the casing, said radiator being spaced from and having a flue connection with the fire box, a chamber at the front of the casing above the fire box, a plurality of heating tubes arranged in tiers in the upper part of the casing, the upper tier of tubes having their ends opening into the chamber and 80 radiator and the lower tier having one end opening into the said chamber, and a flue leading to an outlet flue and with which the other ends of the lower tier of tubes are connected.

2. In a device of the kind described; the combination of a casing, a fire-box located in the front end of said casing, a radiator located at the rear of the casing, means establishing communication between the fire-box and the radiator, a plurality of heating tubes communicating with the front wall of the radiator near the top thereof and extending toward the front of the casing, a chamber at the front of the casing and communicating with the front ends of said tubes, additional tubes communicating at their front ends with said chamber, and a flue extending through the radiator and connecting the rear ends of the last named tubes 100 with an outlet flue.

3. In a device of the kind described, the combination of a casing, a fire-box located in the front end of said casing, a radiator segmental in shape and located at the rear of the casing, said radiator extending from a short distance from the bottom of the casing to the top thereof, a flue connection between the fire-box and the lower portion of the radiator, a plurality of heating tubes communicating with the front wall of the radiator near the top thereof and extending toward the front of the casing, a chamber at the front of the casing and communicating with the front ends of said tubes, additional tubes below the first tubes and communicating at their front ends with said chamber, and a flue connecting the rear ends of the last named tubes with an outlet flue, 115 said flue passing through the radiator from the front to the rear of the same.

4. In a furnace, the combination of a casing, a fire box in the lower front portion of the casing, a radiator in the rear portion of the casing and communicating at its lower 120

- end with the fire box, an outlet flue having a damper controlled connection with the radiator, heating tubes arranged in tiers in the upper part of the casing, the upper tier 5 being connected with the upper end of the radiator, a chamber at the front end of the casing and with which the front ends of the tiers of tubes communicate, and a flue extending through the radiator and connected with the lower tier of tubes and with the outlet flue above the connection of the radiator with said flue.
5. In a furnace, a casing having an air inlet at its lower rear portion, a fire box in the lower front portion of the casing, a segmental-shaped radiator in the rear portion of the casing and extending to the top thereof, a flue connecting the radiator with the fire box, an outlet flue with which the radiator is connected, a chamber at the front of the casing above the fire box, a flue extending through the radiator and connected with the outlet flue above the connection of the radiator with the outlet flue, and heating 20 tubes arranged in tiers in the upper part of the casing, the tubes of the upper tier having their ends opening into the radiator and chamber and the tubes of the lower tier being less in number and having their ends 25 opening into the said chamber and the flue extending through the radiator.
6. A furnace, comprising a casing having an air inlet in its lower rear portion, a fire box in the lower front portion of the casing, a segmental radiator in the rear portion of the casing, said radiator extending a short 30 distance from the bottom of the casing to the top thereof, a flue connecting the fire box with the lower end of the radiator, an outlet flue outside of the casing, a valved connection between the outlet flue and the lower part of the radiator, a chamber in the front of the casing above the fire box, a plurality of heating tubes arranged in tiers in the upper 35 part of the casing, the tubes of the upper tier being of greater number than the lower tier and the tubes of each tier having one end
- opening into the said chamber and the tubes of the upper tier having their other ends opening into the upper end of the radiator, a flue extending through the radiator and into which the tubes of the lower tier open, and a flue connection between the outlet flue and the flue extending through the radiator. 50
7. In a hot air furnace having heating tubes, a casing, a fire box in the lower front portion of the casing, the casing having a rib on its inner front face about on a level with the top of the fire box, a transverse vertical plate between the top of the fire box 55 and top of the casing, said plate extending from side to side of the casing and provided with apertures to receive the ends of the heating tubes and with a foot resting upon the fire box, and a transverse horizontal plate resting upon the foot of the vertical plate and the rib of the casing, said plate extending from side to side of the casing and forming with the vertical plate and the front of the casing, a chamber. 60
8. In a hot air furnace having heating tubes, a casing having a flange on the inner face of its top and a rib on the inner face of its front wall, a fire box in the lower front portion of the casing, a radiator in the rear 65 portion of said casing, a vertical plate having a foot resting upon the fire box and engaging the flange of the top of the casing, said plate being apertured to receive the heating tubes and extending from side to 70 side of the casing, longitudinal rods secured to the radiator and the vertical plate, and a horizontal plate resting upon the rib of the casing and the foot of the vertical plate and forming with the vertical plate and the front of the casing, a chamber. 75
- In testimony whereof I have signed my name to this specification in the presence of two subscribing witnesses.
